Attorney

UNITED STATES PATENT OFFICE

CHARLES H. JONES, OF PHILADELPHIA, PENNSYLVANIA, ASSIGNOR TO UNION SPECIAL MACHINE COMPANY, OF CHICAGO, ILLINOIS, A CORPORATION OF ILLINOIS

PRESSER FOOT FOR SEWING MACHINES

Application filed September 13, 1928. Serial No. 305,841.

The invention relates to new and useful improvements in a presser foot for sewing machines, and more particularly to a presser foot for guiding the upturned edge portions of fabric sections for trimming and for turning down the trimmed portions into flat relation for stitching.

An object of the invention is to provide a presser foot of the above type having a channel for directing the upturned edge portions of fabric sections to the trimming devices and rigid sections at each side of said channel, with a yielding member on the under face of one of said sections, which yielding member may move to a position flush with the under face of the presser foot or to a position projecting below said under face of the presser foot as the thicknesses of the fabric sections being stitched vary one relative to the other.

20 In the drawings:—

Figure 1 is a top plan view of a presser foot embodying the improvements.

Fig. 2 is a bottom plan view of the same.

Fig. 3 is a side view of the presser foot.

25 Fig. 4 is a longitudinal section through the foot portion at one side of the channel.

Fig. 5 is a view similar to Fig. 2 but showing a slightly modified form of presser foot, in that only one yielding member is used.

30 The invention is directed to a presser foot for a sewing machine for producing a flat seam. Associated with the presser foot are horizontally disposed trimming devices. The presser foot is provided with a channel 3 for directing the upturned edge portions of fabric sections to the trimming devices, and also with means for turning down the trimmed edge portions into flat lapped position for stitching. It is quite important that

40 the upturned edge portions shall be under control throughout the entire movement of said edge portions to and from the trimming mechanism. Sometimes the thickness of the fabric sections vary relative to each other.

45 The presser foot of the present invention is provided with a channel through which the upturned edge portions are led to the trimming mechanism and the portions of the foot along the channel are rigid relative to each other. In the under face of one of the foot

sections there is a recess extending longitudinally thereof. Attached to this foot section is a flat spring member which lies in the recess. This flat spring member may move from position beneath the lower face of the section of the presser foot carrying the said member to a position flush therewith.

Referring more in detail to the drawings, the presser foot which embodies the invention includes a shank portion 1 to which is rigidly attached a foot portion 2. There is a channel 3 leading in from the front end of the foot portion which is adapted to receive the upturned portions of fabric sections. The foot portions 4 and 5 alongside of the channel are rigid. Attached to the section 5 is a stationary trimming blade 6. Cooperating with this stationary trimming blade is a movable trimming blade 7 which passes over the rigid section 4 of the presser foot. The channel 3 leads to the opening 8 for the needles. Extending into this opening are stitch fingers 9. The side walls of the presser foot in rear of the trimming devices are constructed so as to lay the trimmed edge portions down one on the other. These parts are of the usual construction in this type of presser foot. The rigid portion 4 of the presser foot is provided with a channel 10 extending the full length thereof. A flat spring 11 is secured to the upper face of this flat portion 4 by a suitable screw 12. The flat spring 11 extends around the toe and lengthwise of the recess 10. The extreme rear end of the flat spring is turned up as indicated at 13. Said end is free however from connection with the foot portion. When the presser foot is raised this spring member 11 will take a position slightly beneath the lower face of the foot portion 4 and when put under pressure this spring member 11 will yield and become housed within the recess so that the lower face of the spring member is substantially flush with the lower face of the foot portion 4.

As shown in Figs. 1 and 2 of the drawings the foot portion 5 is also provided with a recess 14. A flat spring member 15 is secured to the foot portion 5 in a manner similar to the securing of the flat spring mem-

ber 11. This flat spring member 15 extends around underneath the foot portion 5 and lies in the recess 14. This spring member likewise is flush with the under face of the foot section 5 when pressure is applied thereto, and when excessive pressure is released, then said spring member will be moved to a position slightly beneath the lower face of the foot section 5. As shown in Fig. 5 of the drawings, only one yielding member is provided and the section 5 of the foot is solid and of the usual construction. As is clearly shown in the drawings the groove in the presser foot is of a depth equal to the thickness of the spring member so that when the spring member is forced into the recess it forms a foot section which is to all essential purposes a solid foot section as has already been stated. Furthermore, the rear end of the spring member is bent upwardly as indicated at 13 in the drawings, and when the spring members are moved from the recess to engage the fabric this upturned end remains between the side walls of the recess and operates to prevent said spring member from shifting laterally relative to the channel in the presser foot through which the upturned edge portions of the fabric sections are guided. When the edge portions are being trimmed it is essential that the fabric sections do not shift laterally as they are fed beneath the presser foot, and, therefore, it is very essential that these yielding members be held against any lateral movement when pressing on and controlling the fabric sections.

The operation of the machine is such that if two thicknesses of material are fed under the foot section 5 and only one thickness under the foot section 4, then the spring member 11 will yield so as to engage the single thickness of fabric and hold said single thickness against the work support and in proper engagement with the feed sections of the feed dog. When the presser foot is equipped with a spring member on the under face of the foot section 5 and two thicknesses of fabric are fed under the foot section 4 and only one thickness under the foot section 5, then the yielding spring member 11 due to the pressure of the spring on the presser bar which is greater than the yielding spring action of the member 11 will cause said member to move into the recess and lie flush with the under face of the foot section 4. At this time, however, the yielding member 15 will move downward out of its recess and into contact with a single thickness of fabric and properly hold said single thickness in contact with the work support or the feed sections of the feed dog. When the fabric thicknesses are the same on both sides of the channel, then the yielding members will be housed within the recesses provided therefor, and will be substantially flush with

the under face of the foot sections. The foot sections in this case will operate precisely as if they were solid foot sections.

The presser foot is cut away or is provided with a space on the under face thereof in rear of the needle opening 8. Located in this recess or space is a yielding section 16 which extends all the way across the presser foot. Said yielding section is carried by vertically extending members 17, 17. Springs 18 bearing on said yielding section normally force said yielding section in a downward direction. A suitable stop is provided for limiting the movement of this yielding section 16. The stop, however, is so positioned that the yielding section may move so that its under face is above a plane containing the under face of the foot sections 4 and 5, and on the other hand it is also capable of moving to a position where the under face is beneath a plane containing said under face of the foot sections. This yielding section in rear of the needle opening is for the purpose of taking care of cross seams, elastic tapes, and the like. The yielding section 16 is provided with a clearance space 19 directly in rear of the needle opening 8 to prevent the enchain thread loop during chaining off from being cut by the feed dog.

It is obvious that minor changes in the details of construction and the arrangement of parts may be made without departing from the spirit of the invention as set forth in the appended claims.

Having thus fully described my invention, what I claim as new and desire to secure by Letters Patent, is:—

1. The combination of horizontally disposed trimming devices, a presser foot associated therewith and having a channel for directing the upturned edge portions of fabric sections to said trimming devices and having means for turning down the trimmed portions into flat lapping relation, the foot portions of said presser foot along the side of said channel being rigidly supported by the shank of the presser foot, one of said foot portions having a recess in its under face, a spring member attached to said foot portion and extending from front to rear of said foot portion in said recess, said spring member being normally disposed beneath said foot portion when free from pressure and being flush with the foot portion when under pressure, said spring member having the free end thereof shaped so as to remain at all times under the lateral control of the side walls of the recess.

2. The combination of horizontally disposed trimming devices, a presser foot associated therewith and having a channel for directing the upturned edge portions of fabric sections to said trimming devices, and having means for turning down the trimmed portions into flat lapping relation, the foot por-

tions of said presser foot along the side of said channel being rigidly supported by the shank of the presser foot, each of said foot portions having a recess formed in its under face and extending from front to rear thereof, and a yielding spring member attached to each foot portion and disposed in said recess and adapted to move from a position flush with the under face of the foot portions when 5 under pressure to a position beneath said foot portions when relieved from excessive pressure, the free end of each of said spring members being shaped so as to remain at all times under the lateral control of the side 10 walls of its associated recess.

3. The combination of horizontally disposed trimming devices, a presser foot associated therewith and having a channel for directing the upturned edge portions of fabric sections to said trimming devices, and having means for turning down the trimmed portions into flat lapping relation, the foot portions of said presser foot along the sides of said channel being rigidly supported by 20 the shank of the presser foot, said foot portions at the sides of the channel terminating substantially in line with the rear side of the needle opening, one of said foot portions having a recess in its under face extending from 25 front to rear, a flat spring member attached to said foot portion and lying in said recess and adapted to move from a position flush with the under face of the foot portion to a position beneath the same, said presser foot 30 having a yielding section extending all the way across said presser foot and disposed directly in rear of the needle opening.

4. The combination of horizontally disposed trimming devices, a presser foot associated therewith and having a channel for directing the upturned edge portions of fabric sections to said trimming devices, and having means for turning down the trimmed portions into flat lapping relation, the foot 40 portions of said presser foot along the sides of the channel being rigidly supported by the shank of the presser foot, said foot portions at the sides of the channel terminating substantially in line with the rear side of the needle opening, one of said foot portions having a recess in its under face extending from front to rear, a flat spring member attached to said foot portion and lying in said recess and adapted to move from a position flush 45 with the under face of the foot portion to a position beneath the same, said presser foot having a yielding section extending all the way across said presser foot and disposed directly in rear of the needle opening, said 50 yielding portion having a clearance space at its front side directly in rear of the needle opening.

In testimony whereof, I affix my signature.
CHARLES H. JONES.
